Primary Examiner — Cynthia M Chin(74) *Attorney, Agent, or Firm* — McDermott Will & Emery LLP(57) **CLAIM**

We claim the ornamental design for a ride on vehicle, as shown and described.

DESCRIPTION

FIG. 1 is a front right side perspective view of a ride on vehicle according to the new design.

FIG. 2 is a left rear side perspective view of the ride on vehicle shown in FIG. 1.

FIG. 3 is a right side view of the ride on vehicle shown in FIG. 1.

FIG. 4 is a left side view of the ride on vehicle shown in FIG. 1.

FIG. 5 is a top plan view of the ride on vehicle shown in FIG. 1.

FIG. 6 is a bottom plan view of the ride on vehicle shown in FIG. 1.

FIG. 7 is a front view of the ride on vehicle shown in FIG. 1; and,

FIG. 8 is a rear view of the ride on vehicle shown in FIG. 1. Features shown in broken lines in the drawings are not part of the claim.
